United States Patent Office.

JOHN OWEN, OF DAYTON, OHIO, ASSIGNOR TO HIMSELF, HENRY L. BROWN, AND A. BARR IRWIN, OF SAME PLACE.

Letters Patent No. 84,438, dated November 24, 1868.

IMPROVEMENT IN PATTERNS FOR STOVES AND HOLLOW WARE.

The Schedule referred to in these Letters Patent and making part of the same.

To all whom it may concern:

Be it known that I, JOHN OWEN, of Dayton, in the county of Montgomery, and State of Ohio, have invented a new and useful Improved Mode of Constructing Patterns for Casting Stoves, Hollow Ware, &c.; and I do hereby declare that the following is a full, clear, and exact description of the same, reference being had to the annexed drawings, making part of this specification, in which—

Figure 1 is a plan,

Figure 2, an elevation of a pot-pattern.

Figure 3, an elevation showing the mode of constructing the pot-patterns, and

Figure 4 is a section of the stove-plate pattern.

The same letters in all the figures are used to indicate the same parts.

My invention consists in constructing patterns for casting stove-plates and hollow ware from paper, as set forth in the following specification.

Stoves and hollow ware are, ordinarily, cast from iron patterns. These patterns are cast from others, made of wood. As it is desirable that the plates should be thin, the wood must of course be cut down to the requisite thinness. This operation is performed by hand, and is very expensive. The wooden patterns thus constructed, when placed in the sand, in forming the mould, become damp, and when removed they are liable to warp, and be consequently spoiled. Besides this, being composed of many pieces, they are liable to be split or broken in "rapping" them, in order to draw them from the mould. The wooden patterns of pots are composed, necessarily, of a great number of pieces glued together, and are both expensive and fragile.

In order to remedy these objections to the wooden patterns heretofore required, I have substituted sheets

of paper, which may be made of whatever thickness it is desired to have the patterns.

The stove-plate patterns, A, fig. 1, being cut to the requisite form, are of a uniform thickness. Fillets, B, being cut to the desired form, are attached to the edges of the plate by glue, to make whatever edges or rims may be desired, and when completed, the whole is coated with varnish.

To make the patterns for the hollow ware, I first make a block or former, of the required internal size. Around this I place a conical sheet of paper, having the edges glued together, of the size and shape of the top of the pot. The bottom is formed by cutting out triangular pieces from the small end of the paper cone, so as to leave points, which, when folded down over the block, will close their edges, one against the other, forming a rounded bottom for the pot, of the exact form of the block. The edges thus matched are glued together, and the whole protected by a coating of varnish.

By this means, I am enabled to produce patterns at a very small percentage of the ordinary cost of wooden patterns, and which have been found, on trial, to be superior, as not being affected by the dampness of the sand, nor liable to crack or warp from climatic influences.

What I claim as my invention, and desire to secure by Letters Patent, is—

Patterns, for casting stove-plates and hollow ware, made of paper, substantially as set forth.

In testimony whereof, I have signed my name to this specification, in the presence of two subscribing witnesses.
